UNITED STATES PATENT OFFICE.

DAVID H. WILSON, OF MIAMI, FLORIDA.

VARIOCOUPLER

Application filed February 17, 1925. Serial No. 9,786.

To all whom it may concern:

Be it known that I, DAVID H. WILSON, a citizen of the United States, residing at Miami, in the county of Dade and State 5 of Florida, have invented certain new and useful Improvements in VarioCoupler, of which the following is a specification.

This invention relates to wireless telegraphy and telephony and has special reference to a variocoupler for such purposes.

More particularly the invention relates to what I preferably term a dynamic octapole variocoupler.

One important object of the invention is 15 to provide an improved general construction for devices of this character.

A second important object of the invention is to provide a variocoupler having an improved pole arrangement.

20 A third important object of the invention is to provide an improved variocoupler having double the number of poles usually found in such instruments.

25 A fourth important object of the invention is to provide an improved variocoupler wherein the poles are divided into sets and in which the winding is such that one set of poles is reversely arranged with respect to the other so that a balancing effect is 30 obtained.

With the above and other objects in view as will be hereinafter apparent, the invention consists in general of certain novel details of construction and combinations of 35 parts hereinafter fully described, illustrated in the accompanying drawings and specifically claimed.

In the accompanying drawings like characters of reference indicate like parts in 40 the several views, and:

Figure 1 is a side elevation of a variocoupler constructed in accordance with this invention.

Figure 2 is a view showing the tubes on 45 which the wire of the variocoupler is wound, the view being partly a section on the line 2—2 of Figure 1.

Figure 3 is a view showing the directions in which the wire is wound on the rotatable members of the variocoupler.

Figure 4 is a view showing the direction in which the wire is wound on the elationary members of the variocoupler.

50 Figure 5 is a wiring diagram of the device, the diagram being shown in connec-

tion with a typical wireless receiving circuit.

One typical embodiment of the invention is shown in the accompanying drawings and will be described in detail. It is to be understood, however, that the present disclosure is merely typical of the invention and that the latter may be modified in form and detail to suit different conditions of use.

60 In the present embodiment there is provided a base 10 of rectangular form and preferably constructed of some suitable dielectric substance such as hard rubber, bakelite, or other well known substance of 70 this class. The base may, however, in some instances, be of metal and, in other instances, may be omitted as when the device is mounted in a cabinet, in which case the floor of the cabinet may constitute the 75 base.

On this base are mounted the guides 11 which are preferably in the form of a pair of parallel strips arranged adjacent to the side edges of the base and extending longitudinally of said base. Slidably mounted on these guides is a pair of L-shaped brackets 12 which are arranged in confronting relation as shown in Figure 1. Close to each end of the base on the center line thereof is a small bracket 13 through which passes the shank portion of an adjusting screw 14 having a knurled head 15 on one side of the bracket and a collar 16 on the other. By this arrangement the screw may 80 be rotated without moving longitudinally in the bracket 13. The threaded portion of each screw is screwed through the upright part of a respective L-shaped bracket 12 so that rotation of these screws adjusts the 85 bracket 12 toward and from the center of the base, it being noted that, as the screws are independent, the brackets are independently adjustable.

Secured to the inner face of the upright portion of each bracket 12 is a pair of tubes 17 made of some suitable dielectric material such as those mentioned above. The tubes of each pair are arranged in parallel spaced relation as can be clearly seen by reference 100 to Figure 2 and also the tubes of one pair are axially alined with the tubes of the other pair as can likewise be noted by reference to Figure 2 and to Figure 1.

105 On the transverse center line of the base 110

is mounted a pair of upstanding brackets 18, each being positioned at a respective side of said base. These brackets having suitable bearing openings in their upper ends to rotatably support a shaft 19, the axis of which intersects the axes of the tubes 17 at right angles thereto. Thus the axes of the tubes and shaft all lie in the same plane parallel to the base 10. On this shaft is mounted a 10 pair of short tubes or rings 20 of dielectric material. The axes of these tubes are at right angles to the axis of the shaft 19 and intersect the axis of the tubes 17. On one end of the shaft is mounted suitable means 15 for turning the same as indicated by the knob 21 of the dial 22. It will now be plain that the tubes or rings 20 may be rotated between positions at right angles to the tubes 17 and positions in alinement therewith and 20 it is to be noted that the mounting is such that either end of a tube 20 may be brought, at will, adjacent a respective tube 17.

By reference to Figures 3, 4 and 5 it will be seen that one of the rings is provided 25 with a right hand winding 23 while the other has a left hand winding 24 in series therewith. Similarly one of each pair of tubes 17 is provided with a right hand winding 25 while the other of said pair is provided with 30 a left hand winding 26 and it will be noted from Figure 4 that the right hand windings are on diagonally disposed tubes as are the left hand windings. Thus the tubes of an alined pair are wound to opposite hands.

35 As shown in Figure 5 one end of the winding 25 of one tube is connected to a terminal 27 while the other end of such winding is connected by a wire 28 with the winding 26 of the companion tube on the respective 40 bracket. The remaining end of the winding 26 is connected by a wire 29 with one end of the winding 25 of the alined tube and this winding is, in turn, connected by a wire 30 with one end of the remaining winding 26. 45 This last winding has its end connected to a terminal 31.

The aerial 32 is connected to a switch arm 33 traversing contacts 34 tapped off the first 50 winding 25 by wires 35 and tapped off the second winding 26 by wires 36. Similarly the ground 37 is connected to the remaining windings 25 and 26 by a switch arm 38 traversing contacts 39 which are connected to said windings by wires 40 and 41.

55 The free end of the secondary winding 23 is connected to a terminal 42 and the free end of the winding 24 is connected to a terminal 43.

60 Taps 44 and terminals 45 may be also used on the wire 29 and the terminals 42 and 43 are used to connect the variometer to the remainder of a receiving apparatus such as is shown at 46, it being understood that this showing is merely to indicate one use to 65 which the improved variometer may be put.

From the foregoing it will be seen that the windings 25 and 26 are connected throughout in series. At the same time it will be observed that the winding of one stator in each pair is connected in multiple to the winding 70 of the other stator of said pair.

It is to be noted that the windings shown in Figures 3 and 4 are merely typical and are intended only to indicate directions and 75 not number of turns or size of wire.

It will now be seen that this arrangement constitutes a parallel arrangement of variocouplers wherein the two variocouplers have their magnetic poles inverted with respect to each other and that this inverted condition 80 exists in both stator and rotor elements and persists under all variations in the position of the rotor element.

Experience has shown that the use of this dynamic octapole variocoupler in a set eliminates the necessity for variometers, additional honey comb or spider web coils or other like devices such as are commonly used in the better types of radio sets, the same 85 effects being produced as with the more complicated and expensive arrangements.

In tuning with the dynamic octapole variocoupler Figure 5 plainly indicates the different sections that the variocoupler is wound with, and also by the movement of these switches where these said sections may be cut in and out on both fields of the variocoupler. While these two switches can be operated by one movement, I find it is absolutely essential that they should be worked 100 independent of each other in order to cover a large field of distances and stations. For example, if the aerial switch is on No. 1 button and the ground switch is on No. 4 button, New York and all New England stations 105 come in very clear and loud, but if ground switch No. 1 is thrown on No. 1 button and aerial switch is placed on No. 5 button, these stations will come up like thunder in the receivers, as will also Mexico city, California 110 and the most distant stations when they are tuned in with the variable condenser.

Experience also shows that this dynamic octapole variocoupler covers a range of distance that have never yet to my knowledge 115 been attained by any other receiving apparatus devised up to date.

In operation I find that by a movement of the rotors I can cut in and cut out long distant stations without changing the position of the points on the dial of the variable condenser. I can also either increase or decrease the volume of sound from all stations without changing the position of the points 120 on the dial of the variable condenser. After picking up a station faintly I can by movement of the point on the dial of the variable condenser from one to fifteen degrees bring the volume of this station up to its peak of 125 loudness.

As already explained, with the addition of these two switches I can make any number of different combinations for bringing up stations, near or far.

5 I also in the construction of this dynamic octapole variocoupler show a design whereby the field is what I term a complete closed magnetic field that may be strengthened or weakened at will, thereby having an efficiency substantially 100%.

10 There has thus been provided a simple and efficient device of the kind described and for the purpose specified.

15 It is obvious that minor changes may be made in the form and construction of the invention without departing from the material spirit thereof. It is not, therefore, desired to confine the invention to the exact form herein shown and described, but it is 20 desired to include all such as properly come within the scope claimed.

Having thus described the invention, what is claimed as new, is:

25 1. A variocoupler instrument including a pair of stators having windings connected in series and wound in opposite directions, a pair of rotors having windings in opposite directions and connected in series, each rotor being associated with a respective stator, a common rotatable support whereon said rotors are mounted, and a second pair of stators opposite the first pair and having windings connected in series and wound in opposite directions, the second pair of 30 stators being connected in series to the first pair and having their respective windings in directions opposite to the opposed stators of said first pair.

35 40 2. A variocoupler instrument including a pair of stators having windings connected in series and wound in opposite directions, a pair of rotors having windings in opposite directions and connected in series, each rotor being associated with a respective stator, a common shaft whereon said rotors are fixed with their axes parallel to each other and at right angles to the axis of the shaft, and a second pair of stators opposite the first pair and having windings connected in series and wound in opposite directions, the second pair of 45 stators being connected in series to the first pair and having their respective windings in directions opposite to the opposed stators of said first pair.

50 55 3. A variocoupler instrument including a pair of stators having windings connected in series and wound in opposite directions, a pair of rotors having windings in opposite directions and connected in series, each rotor being associated with a respective stator, and a common rotatable support whereon said rotors are mounted, a second pair of stators opposite the first pair and having windings connected in series and wound in opposite directions, the second pair of 60 65 stators being connected in series to the first pair and having their respective windings in directions opposite to the opposed stators of said first pair.

stators being connected in series to the first pair and having their respective windings in directions opposite to the opposed stators of said first pair, and means to move said stators toward and from said rotors.

70 4. A variocoupler instrument including a pair of stators having windings connected in series and wound in opposite directions, a pair of rotors having windings in opposite directions and connected in series, each rotor being associated with a respective stator, a common shaft whereon said rotors are fixed with their axes parallel to each other and at right angles to the axis of the shaft, a second pair of stators opposite the first pair and having windings connected in series and wound in opposite directions, the second pair of stators being connected in series to the first pair and having their respective windings in directions opposite to the opposed stators of said first pair, and means to move said stators toward and from said rotors.

75 80 85 5. A variocoupler instrument including a pair of stators having windings connected in series and wound in opposite directions, a pair of rotors having windings in opposite directions and connected in series, each rotor being associated with a respective stator, and a common rotatable support whereon said rotors are mounted, a second pair of stators opposite the first pair and having windings connected in series and wound in opposite directions, the second pair of stators being connected in series to the first pair and having their respective windings in directions opposite to the opposed stators of said first pair, and means to move said stators toward and from said rotors.

90 95 100 6. A variocoupler instrument including a pair of stators having windings connected in series and wound in opposite directions, a pair of rotors having windings in opposite directions and connected in series, each rotor being associated with a respective stator, a common shaft whereon said rotors are fixed with their axes parallel to each other and at right angles to the axis of the shaft, a second pair of stators opposite the first pair and having windings connected in series and wound in opposite directions, the second pair of stators being connected in series to the first pair and having their respective windings in directions opposite to the opposed stators of said first pair, and means to move said stators toward and from said rotors, said last means being arranged to effect movement of each pair of stators independently of the other pairs.

105 110 115 7. A variocoupler instrument including a pair of stators having windings connected in series and wound in opposite directions, a pair of rotors having windings in opposite directions and connected in series, each rotor being associated with a respective stator, and a common rotatable support whereon said rotors are mounted, a second pair of stators opposite the first pair and having windings connected in series and wound in opposite directions, the second pair of stators being connected in series to the first pair and having their respective windings in directions opposite to the opposed stators of said first pair, and means to move said stators toward and from said rotors, said last means being arranged to effect movement of each pair of stators independently of the other pairs.

120 125 8. A variocoupler instrument including a pair of stators having windings connected in series and wound in opposite directions, a

- 4
- pair of rotors having windings in opposite directions and connected in series, each rotor being associated with a respective stator, a common rotatable support whereon said 5 rotors are mounted, and a second pair of stators opposite the first pair and having windings connected in series and wound in opposite directions, the second pair of stators being connected in series to the first pair and 10 having their respective windings in directions opposite to the opposed stators of said first pair, the winding of one stator in each pair being also connected in multiple to the winding of the other stator of each pair.
- 15 8. A variocoupler instrument including a pair of stators having windings connected in series and wound in opposite directions, a pair of rotors having windings in opposite directions and connected in series, each rotor being associated with a respective stator, a 20 common shaft whereon said rotors are fixed with their axes parallel to each other and at right angles to the axis of the shaft, and a second pair of stators opposite the first pair and having windings connected in series 25 and wound in opposite directions, the second pair of stators being connected in series to the first pair and having their respective windings in directions opposite to the opposed stators of said first pair, the winding of one stator in each pair being also connected in multiple to the winding of the other stator of each pair.

In testimony whereof I affix my signature.

DAVID H. WILSON.
